UNITED STATES PATENT OFFICE.

LOUIS COMBET, OF PARIS, FRANCE.

POWER-TRANSMITTING MECHANISM FOR BICYCLES.

No. 817,225.

Specification of Letters Patent.

Patented April 10, 1906.

Application filed April 8, 1905. Serial No. 254,455.

To all whom it may concern:

Be it known that I, LOUIS COMBET, a citizen of France, residing at Paris, France, have invented certain new and useful Improvements in Power-Transmitting Mechanism for Bicycles, of which the following is a specification.

This invention relates to a mechanism of power transmission from a pedal mechanism to the driving-wheel and by which the dead-point is suppressed or overcome, and which result is obtained by displacing from the front to the rear one of the shafts or all the crank-shafts at the proper moment, so as to make these cranks lose the center of gravity.

In the accompanying drawings, Figure 1 is a side view of the mechanism. Fig. 2 is a view in plan and section of the rear part of the mechanism. Fig. 3 is a view in plan and section of the forward part. Fig. 4 is a section of one of the eccentrics. Fig. 5 is a view in plan and section of an eccentric arrangement which can be substituted for the device of Fig. 4. Fig. 6 is a side view of a modification of the device of Figs. 1 to 5 shown when passing the dead-point. Fig. 7 is a one-half view in plan and section of the mechanism of Fig. 5 with connection of the eccentrics by means of a rod having a turnbuckle or other stretcher. Fig. 8 is a one-half view in plan and section of the same with connections of the eccentrics by means of a chain. Fig. 9 is a side view both in plan and section of one of the crank-eccentrics of Fig. 6, and Fig. 10 is a side view in plan and section of an eccentric pinion or sprocket of the chain device of Fig. 8.

As shown in Figs. 1 to 5, this power-multiplying mechanism consists of a frame preferably made up of two plates *a*, secured to the frame *b* of the machine, Fig. 1. To the pedal mechanism *c*, which also comprises the pedal-cranks *d*, are hinged two side levers *e*, also fitted to cranks *f*, carrying ball-bearings *g*, Fig. 2. Through the case *g'* of this ball-bearing passes the axle *h* of a resistance-cam *i*, fixed by means of a conical part *i'*, and a screw-threaded part on which fits an exterior nut *j*. The case *g'* is bolted to a plate *k* of circular shape, which is held by four eccentrics *s* (shown in section in Figs. 4 and 5) and connected with the frame *a* of the mechanism. This eccentric arrangement serves to annul or overcome the dead-point. Between the disk *k* and the frame *a* are fixed both front and rear friction-rollers *l*, which

serves as points of support for the corresponding resistance-cam *i*, which produces the power of the levers. This power is transmitted by the levers *e* and rods *m*, fixed and regulated by frames *m'*, through which rotatably passes the outwardly-extending pin or projection *m²* of the cranks *n*, Figs. 1 and 3. On the axle *n'* of the cranks *n* is keyed a sprocket-wheel *o*, engaged by chain *p*, which actuates the chain-pinion *q*, Fig. 2, which is secured to the axle of the driving-wheel *r*, Figs. 1, 2, and 3, or otherwise drives it. Owing to this arrangement when the cranks *f* arrive at the dead-point the eccentric or cam *i* presses on the friction-roller *l* at the right in Fig. 1 and forces the axle *h* from the vertical position and inclines the cranks *f* forward and a dead-point is thus avoided. The eccentrics *s* assist in accomplishing the same purpose, and their stress takes effect on the collars *s'*, Fig. 4, which are fixed on their respective plates *k*.

The eccentrics *s* above described may be substituted by the arrangement shown in Fig. 5—that is, by a kind of crank of which one pin *s²* is rotatably engaged in the frame *a* and the other, *s³*, rotatably engaged in the circular plate *k* referred to above. In this figure *s⁴* represents bearings for the axles *s²* and *s³*. These bearings are fixed on their respective pieces *a* and *k* by washers and nuts *s⁵*. With this device in pedaling the motion of the cranks *d* of the pedal mechanism will be reproduced at the eccentric arrangement, which will annul or overcome the dead-point by the displacement of their axles, and simultaneously at the cranks *n*, which will accomplish the movements of the driving-wheel *r*.

As a modification of the devices above described Figs. 6 to 10 show a mechanism which employs a form of frame *a* which differs in details of construction from that shown in Fig. 1. The pedal mechanism *d* is fitted on eccentrics *t* within two collars *t'*, Figs. 6, 7, 8, and 9, and is connected to the rear cranks *u*, having eccentrics *v* similar to the eccentrics *t*, previously described, by means of a rod *w* with stretcher or turnbuckle *x* and set on ball-bearings *t²*, Fig. 9, or the connections between the eccentrics *t* may be obtained, as shown in Figs. 8 and 10, by a chain *y* passing around two pinions *z*, which are eccentrically mounted on the two axles, one of which, *z'*, belongs to the pedal mechanism and the other, *z²*, to the crank *d*. The axle *a'*, Fig. 6, of the driving-wheel *r* can be regulated by

means of a stretcher with set-screw b' , which determines the tension of the chain p , connecting the driving-pinion with the upper chain-wheel o . For that purpose there are 5 arranged in the body of the frame a two oblique slots a^2 to allow a displacement of the axle by means of a structure with set-screw b' .

I claim—

- 10 1. In a power-multiplying mechanism for bicycles and the like, a pedal mechanism including pedal-cranks, lever-bars connected with and operated by said cranks, rear cranks rotatively connected with the lever-bars, shifting-cams driven by said rear cranks, rollers engaged by said cams, power-transmission cranks and connections therefrom to the lever-bars aforesaid, and connections from the power-transmission cranks to the 15 driving-wheel of the bicycle.
- 20 2. In a power-multiplying mechanism for bicycles and the like, a pedal mechanism including pedal-cranks, lever-bars connected

with and operated by said cranks, rear cranks rotatively connected with the lever-bars, 25 shifting means operated by said rear cranks, power-transmission cranks and connections therefrom to the lever-bars aforesaid, and connections from the power-transmission cranks to the driving-wheel of the bicycle. 30

3. In a power-multiplying mechanism for bicycles, and the like, a pedal mechanism including pedal-cranks mounted upon eccentrics, lever-bars connected with and operated by said cranks, rear cranks rotatively connected with the lever-bars, shifting means for the rear cranks, connected with the pedal-eccentrics, and power-transmission connections from the lever-bars to the driving-wheel of the bicycle. 40

In testimony whereof I affix my signature in presence of two witnesses.

LOUIS COMBET.
